(57) CLAIM

The ornamental design for a base for vacuum cleaner, as shown and described.

DESCRIPTION

FIG. 1 is a perspective view of a base for vacuum cleaner showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is an enlarged top plan view thereof; and,

FIG. 7 is an enlarged bottom plan view thereof.

The portions shown in dashed lines in FIGS. 1-7 form no part of the claimed design.
